(57) **CLAIM**

The ornamental design for a surgical tray for dental implants, as shown and described.

DESCRIPTION

FIG. 1 is a front-right-top perspective view of a surgical tray for dental implants showing environment according to the present invention;

FIG. 2 is a front-right-top perspective view of FIG. 1 without the environment;

FIG. 3 is a top plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is a front-right-top perspective view thereof in a disassembled state.

The dash lines in form of a case and dental implants in FIG. 1 depict environmental subject matter and form no part of the claimed design. All the other dash lines in the figures depict portions of the surgical tray for dental implants that form no part of the claimed design.

1 Claim, 5 Drawing Sheets
